UNITED STATES PATENT OFFICE.

BERNHARD B. HARTLEB AND RUDOLPH C. HARTLEB, OF BALTIMORE, MARYLAND.

AUTOMATIC BABY-CARRIAGE FAN.

1,218,858.

Specification of Letters Patent.

Patented Mar. 13, 1917.

Application filed August 19, 1916. Serial No. 115,893.

To all whom it may concern:

Be it known that we, BERNHARD B. HARTLEB and RUDOLPH C. HARTLEB, citizens of the United States, residing at Baltimore, in the State of Maryland, have invented certain new and useful Improvements in Automatic Baby-Carriage Fans, of which the following is a specification, reference being had to the accompanying drawings.

10 This invention relates to an improved automatic baby carriage fan and has for its primary object to provide a very simple and effective mechanism for imparting a vertical swinging movement to a fan supported over 15 the carriage.

It is another object of the invention to provide improved means for mounting the operating mechanism whereby the device may be easily and quickly applied to or removed 20 from baby carriages, go-carts, toy wagons, and similar vehicles.

The invention has for another important object to provide improved means for mounting and adjusting the fan supporting 25 or carrying rod so that it can be disposed out of the way in placing the infant in the carriage or removing him therefrom, and also adjusting the support to properly position the fan over the carriage.

30 With the above and other objects in view, our invention consists in the novel features of construction, combination and arrangement of parts to be hereinafter more fully described, claimed and illustrated in the accompanying drawing, in which,

Figure 1 is a side elevation showing our improved automatic fan applied to a baby carriage;

Fig. 2 is an inner side elevation of the device;

Fig. 3 is a section taken on the line 3—3 of Fig. 2;

Fig. 4 is a section taken on the line 4—4 of Fig. 2;

45 Fig. 5 is a fragmentary elevation illustrating a slightly modified means for adjustably mounting the base bar upon the carriage;

Fig. 6 is a section taken on the line 6—6 of Fig. 5;

Fig. 7 is a detail perspective view of certain of the parts.

Referring in detail to the drawing, 5 designates the base bar of a supporting frame, to which the lower end of a standard or upright 6 is riveted or otherwise securely fixed,

The ends of this base bar, as shown in Fig. 2, are flanged for engagement with reinforcing ribs or cleats on the inner face of the carriage wall. The bar 5 is provided with a short vertical slot 7 therein through which the threaded bolt 8 is disposed and is vertically adjustable. A wing nut 9 is threaded upon the inner end of said bolt and, to the outer end thereof, a hook 10 is fixed for engagement over the upper edge of the carriage. By adjusting the nut 9, the hook may be drawn into tight clamping engagement with the carriage wall.

A bracket 11 is fixed at one of its ends to the standard 6 and has a vertically disposed portion extending in spaced parallel relation to said standard. A shaft 12 is mounted to rotate in the standard and said bracket, and upon this shaft a sprocket wheel 13 is suitably secured. This wheel is connected by means of a drive chain 14 to a larger sprocket wheel 15 fixed to the hub of one of the front vehicle wheels of the carriage. Upon the inner end of the shaft 12, a disk 17 is suitably secured and is provided with an eccentrically disposed wrist pin 18. Immediately below said disk, a horizontally disposed arm 19 is fixed to the upright or standard 6, and to this arm the lower end of a vertically disposed bar 20 is secured. In the upper end of said bar, a pin or stud 21 is fixed. An arm 22 is provided with a longitudinally extending slot 23 to receive the pin 21, said arm sliding freely between spaced washer plates 24 engaged upon said pin. One end of the arm 22 is loosely mounted upon the wrist pin 18 and held in connection therewith by means of a suitable key indicated at 25, a similar key 26 disposed through the end of the pin 21 also preventing shifting movement of the arm 22 longitudinally on said pin.

A rod 27 is slidably engaged in the other end of the arm 22 and extends inwardly and at right angles to said arm. A sleeve 28 projects from the inner face of the arm 22 and is integral therewith or secured to the same in any approved manner. A pin indicated at 29 projects from the other end of this sleeve in spaced relation to the rod 27. A collar 30 is loosely mounted upon the rod 27 and is provided with spaced shoulders 31. This collar carries a set screw 32 for binding engagement with the rod 27 to rigidly fix the collar thereon. A similar collar 33 is secured by means of the set screw 34.

on the outer end of the rod 27, and a clamping screw 35 is threaded in the sleeve 28, whereby the rod may be securely held against turning movement in the arm 22.

5 The inner end portion of the rod 27 is angularly disposed, as at 36, to extend longitudinally in a rearward direction over the carriage, and upon the inner end of this portion 36 of the rod a stop shoulder 37 is provided. A sleeve or tube 38 is adjustably engaged upon the longitudinal end portion 36 of the rod and carries a set screw 39, whereby said sleeve may be securely fixed in its adjusted position upon said rod. The 10 sleeve 38 is formed upon one end with a suitable socket to receive the shank of a fan, indicated at F, and the clamping screw 40 is threaded in the wall of the socket to engage said shank, whereby the fan may be detachably held in connection with the sleeve. The 15 inner longitudinally disposed end portion of the rod 27 may be disposed at any desired angle over the carriage, by loosening the screw 35 and the screw 32 on the collar 30 so that the rod 27 may be turned in the end of the arm 22. These screws are then properly 20 tightened, it being understood that one of the shoulders 31 on the collar 30 is in contact with the pin 29. In this position, the angular end portion 36 of the rod projects 25 rearwardly over the carriage. In placing the infant in the carriage or removing him from the same, the screw 35 is loosened and the end 36 of the rod 27 is swung upwardly 30 and forwardly until the other stop shoulder 31 on the collar 30 engages with said pin. The fan F having been fixed in the 35 sleeve 38, the rod is returned to its former position and the screw 35 then tightened 40 thereon. As the carriage is pushed or propelled, rotation will be transmitted to the shaft 12 from the front wheel of the carriage, and the arm 22 will be shifted longitudinally and vertically oscillated upon the 45 pin 21 by reason of its eccentric connection to the disk 17. In this movement of the arm, it will be readily seen that as the rod 27 is rigidly fixed thereto, the fan F will be vertically swung or oscillated, and will agitate 50 the air and direct the air toward the infant in the carriage.

In some carriage constructions, it may not be possible to apply the device by means of the base clamp above described, and we have, 55 therefore, illustrated in Figs. 5 and 6 of the drawing another form of support which may be used where the wall of the carriage is flush on its inner and outer faces and not provided with reinforcing ribs or cleats. In 60 this construction, a clamp of substantially inverted U-shape form, indicated at 41, is engaged over the upper edge of the carriage wall and a set screw 42 is threaded in the arm of the clamp which is disposed upon 65 the outer face of the wall for binding en-

gagement with said wall to hold the clamp in its applied position. An upstanding loop 43 is integrally formed upon the medial portion of the clamp and, in the same, the base bar 5' is slidably engaged. A set screw 70 44 is also threaded in one side of said loop for binding engagement with the base bar to hold the same in its longitudinally adjusted position. The several means which we have shown and described for mounting the mechanism upon the carriage are merely illustrative, and it is to be understood that various other means for clamping or mounting the supporting frame upon the carriage may be substituted in lieu thereof.

75 From the foregoing description, taken in connection with the accompanying drawing, the construction and manner of operation of our invention will be clearly and fully understood. The device may be easily and quickly applied to or removed from the carriage and automatically operates the fan or toy in the movement of the vehicle. The fan may be of various shapes and ornamental forms and, if desired, a number of fans may be suitably arranged upon a common rod or staff secured in the sleeve 38.

80 While we have shown and described the preferred form, construction and arrangement of the several elements employed, it is also to be understood that the same are susceptible of considerable modification therein and we, therefore, reserve the privilege of resorting to all such legitimate changes as may be fairly embodied within the spirit 90 and scope of the invention as claimed.

85 The sprocket 15 may be clamped or otherwise suitably attached to the hub of the ordinary carriage wheel without requiring any structural changes in the latter. The oscillatory fan F also obviates the possibility 95 of flies or other insects annoying the infant.

90 Having thus fully described our invention, what we desire to claim and secure by Letters Patent is:—

100 1. The combination of a support, a shaft mounted in the support, an arm slidably supported intermediate of its ends and eccentrically connected at one of its ends to 105 said shaft, means for attaching a fan to the other end of said arm, and means for rotating the shaft, whereby the arm is oscillated to impart a bodily movement to the fan.

110 2. The combination of a support and means for detachably clamping the same upon a vehicle, a shaft rotatably mounted in said support, a driving connection between said shaft and one of the vehicle wheels, an arm operatively connected to 115 said shaft and supported for sliding and vertical oscillatory movement, an angular rod, means for securing a fan to one end of said rod, and means for adjustably clamping the other end of the rod to said arm.

3. The combination of a support and means for detachably clamping the same upon a vehicle, a shaft rotatably mounted in said support, a driving connection between said shaft and one of the vehicle wheels, an arm operatively connected to said shaft and supported for sliding and vertical oscillatory movement, an angular rod, means for securing a fan to one end of said rod, the other end of the rod being shiftable in said arm at right angles thereto, a clamping screw to hold the rod against movement with respect to the arm, and means permitting of a limited rotation of the rod with respect to the arm to adjustably position the fan with respect to the vehicle.
4. The combination of a support and means for detachably clamping the same upon a vehicle, a shaft rotatably mounted in said support, a driving connection between said shaft and one of the vehicle wheels, an arm operatively connected to said shaft and supported for sliding and vertical oscillatory movement, an angular rod, means for securing a fan to one end of said rod, a sleeve projecting laterally from said arm, said rod being shiftable through the sleeve, a set screw threaded in the sleeve for engagement with the rod, and means on the rod coöperating with means on said sleeve to permit of a limited turning movement of the rod in said sleeve.
5. The combination of a support and means for detachably clamping the same upon a vehicle, a shaft rotatably mounted in said support, a driving connection between said shaft and one of the vehicle wheels, an arm operatively connected to said shaft and supported for sliding and vertical oscillatory movement, an angular rod, means for securing a fan to one end of said rod, a sleeve projecting laterally from said arm, said rod being shiftable through the sleeve, a set screw threaded in the sleeve for engagement with the rod, and means on the rod coöperating with means on said sleeve to permit of a limited turning movement of the rod in said sleeve.
6. The combination of a support, means for detachably clamping the same upon a baby carriage, a shaft mounted in said support, a driving connection between said shaft and one of the carriage wheels, a disk fixed to the shaft, a slotted arm eccentrically connected at one of its ends to said disk, a pin projecting through the slot in said arm and supporting the same for sliding and vertical oscillatory movement, a fan carrying rod adjustably mounted in the other end of said arm, and means permitting of a limited turning movement of the rod in said arm to position the fan with respect to the carriage.
7. The combination of a support, a shaft mounted in said support, an arm slidably mounted upon said support and operatively connected to one end of the shaft, a fan mounted upon the other end of said arm, and means for rotating said shaft.
8. The combination of a support, a shaft rotatably mounted in said support, an oscillatable arm shiftable with respect to its fulcrum and eccentrically connected at one of its ends to said shaft, means for adjustably mounting a fan upon said arm, and means for rotating said shaft.

In testimony whereof we hereunto affix our signatures in the presence of two witnesses.
